UNITED STATES PATENT OFFICE.

ALFRED MACKAY, OF PHILADELPHIA, PENNSYLVANIA, ASSIGNOR TO GEORGE B. FERRIER, OF MOORESTOWN, NEW JERSEY.

ROTARY DRIER.

1,406,991.

Specification of Letters Patent. Patented Feb. 21, 1922.

Application filed June 3, 1920. Serial No. 386,212.

To all whom it may concern:

Be it known that I, ALFRED MACKAY, a citizen of the United States, residing at Philadelphia, in the county of Philadelphia and State of Pennsylvania, have invented new and useful Improvements in Rotary Driers, of which the following is a specification.

My invention relates to rotary driers, such as are used in the paper making art, and consists in certain improvements I have made in the construction of the cylinders over which the web to be dried passes. These cylinders are heated internally by steam, which necessarily condenses as it gives off its heat. The high speeds at which these cylinders are run in modern practice makes it difficult to remove the water of condensation of the steam, as it is naturally thrown and held out by centrifugal force on the inner periphery of the cylinder. Special means has therefore to be provided to direct the water of condensation away from the periphery and out of the cylinder.

Means for this purpose have heretofore been devised, and my invention constitutes an improvement upon such prior means. It has been proposed to mount a spirally arranged open gutter or conductor on the inner periphery of the cylinder, whereby the water is directed to a reservoir or pocket in one end of the cylinder, from which it is discharged through a pipe running through the cylinder trunnion. Such a construction forms the subject matter of U. S. Patent No. 666,477, issued Jan. 22, 1901, to A. A. Hunting. An improvement upon his means is the subject matter of U. S. Patent No. 1,258,055, issued to C. L. St. Clair and J. H.

Hoffman on March 5, 1918, in which a plurality of spiral or helical ribs are secured to the inner periphery of the cylinder and lead into the outermost convolution of a flat spiral chamber constituting one end of the cylinder.

It has been found, in the use of drying cylinders constructed according to this last mentioned patent, that the water of condensation is not removed completely as fast as it is formed, which difficulty I ascribe to the fact that there are several spaced inlets for the water to enter the spiral chamber and that, therefore, interference between the several streams of water takes

place, which interferes with its smooth and regular outflow.

To remedy this defect, I have devised the construction and arrangement, hereinafter described, in connection with the accompanying drawing, in which:

Fig. 1 is a longitudinal section of one end of a drier cylinder equipped with the water removing means of my invention, and

Fig. 2 is a cross section of the same on the line 2—2 of Fig. 1.

10 is the drier cylinder, provided with the usual journal head 11 and journal or trunnion 12. 13 is the outlet or drain pipe for the condensed steam, leading from the central chamber or pocket 14 and passing out 70 through the other end of the cylinder. Three volute spiral chambers, 15, 16 and 17, convey the water into said pocket, and the helical deflector ribs 18 guide the water into said spiral chambers, the latter being each 75 provided with an inlet 19 at the point where the rib terminates.

There is only one rib and only one inlet for each of the chambers so that the water, introduced thereinto, meets with no obstruction or interference by water entering the same chamber at another point, but is free to flow smoothly and regularly through the chamber into the central pocket. It will be understood that the provision of more than 80 one spiral chamber is not merely for the purpose of increasing the capacity of the water removing means, is in fact not for that purpose at all, but has for its object the prevention of interference in the flow off of 90 the water, which I have found occurs when there is only one spiral chamber with a plurality of inlets.

It will also be evident that my invention is not limited to three spiral chambers or 95 to their arrangement as volute spirals in one end of the cylinder. The essence of the invention lies in the provision of a plurality, two or more, of spiral chambers, each having but one inlet, and with one deflector rib for 100 each chamber leading to said inlet, as expressed in the following claims:

Having thus described my invention, what I claim is:

1. In a steam-heated rotary cylinder, 105 means for removing the water of condensation, comprising a plurality of nested independent spiral chambers leading to a com-

mon outlet, and a deflector rib on the cylinder wall leading into the outer end of each chamber to direct the water thereinto.

2. In a steam-heated rotary cylinder, 5 means for removing the water of condensation, comprising a plurality of volute spiral chambers lying in the same transverse plane of the cylinder and terminating in a common central outlet, and an equal number of helical deflecting ribs secured to the inner periphery of the cylinder to guide the water into said chambers, there being one rib for each chamber.

3. In a steam-heated rotary cylinder, 15 means for removing the water of condensation, comprising three spiral chambers lying in the same transverse plane and terminating at 120° apart, a common drain pipe lying in the axis of the cylinder, and three helical

deflecting ribs on the wall of the cylinder, 20 each of said ribs leading to one of said chambers.

4. In a steam-heated rotary cylinder, 25 means for removing the water of condensation, comprising a plurality of chambers for leading the water from the periphery to the center of the cylinder, each chamber having an opening adjacent the periphery and an opening adjacent the axis of the cylinder, 30 a common chamber into which said last mentioned openings discharge, and means carried by the inner periphery of the cylinder to guide the water into said first mentioned openings.

In testimony whereof I have hereunto set 35 my hand.

ALFRED MacKAY.
